ATTORNEY.

UNITED STATES PATENT OFFICE

KENNETH A. KILBOURNE, OF AZUSA, CALIFORNIA, ASSIGNOR TO OWL FUMIGATING CORPORATION, OF NEW YORK, N. Y., A CORPORATION OF DELAWARE

FUMIGATING APPARATUS

Application filed October 3, 1924. Serial No. 741,517.

This invention relates to fumigation, more particularly to fumigation of enclosed, evacuated or partially evacuated spaces.

It is customary to fumigate various articles, such as bales of cotton, dried fruits, and the like to rid the same of insects which often infest them by placing the articles in a closed space which is then evacuated to a high degree in order to remove the air from the interstices of the article and thus to allow more ready penetration thereof by the fumigant. According to a method used heretofore, liquid hydrocyanic acid was heated to vaporize the same, and the gas was introduced into the space to be fumigated. Immediately thereafter air was introduced so that the resulting pressure tended to quickly force a mixture of hydrocyanic acid gas and air into the article to be fumigated. This procedure gave satisfactory results as far as the fumigation of the article was concerned but the apparatus necessary to accomplish the fumigation was cumbersome in that it required a steam boiler or other heating device to vaporize the fumigant and the flame for heating involved an element of danger because the hydrocyanic acid gas produced is highly inflammable.

My invention is intended to obviate these disadvantages, it being among the objects thereof to devise an apparatus for vacuum fumigation which shall be simple and inexpensive in construction, and easy to operate.

It is a further object of my invention to provide an apparatus which shall be capable of gasifying a liquid fumigant without any heating means. In practicing my invention I provide a structure including a nozzle having therein a needle valve through which liquid fumigant is adapted to pass. The chamber which surrounds the needle valve is placed in communication with the evacuated space to be fumigated and air and atomized fumigant are drawn into the said space and into the articles to be fumigated. The liquid hydrocyanic acid ordinarily used for this purpose contains about 4% water and, in passing through the nozzle, becomes atomized and vaporized, abstracting so much heat from its surroundings that at least part of

the water freezes and obstructs the nozzle preventing the flow of the liquid fumigant. To obviate this I provide one or more air ports in the walls of the chamber surrounding the needle valve, the said ports being so located that air is caused to flow over the needle valve to the nozzle thereof and then into the space to be fumigated. As a result, the sensible heat of the incoming air prevents, to a considerable extent, the lowering of the temperature of the needle valve to a point favorable to the freezing of water thereon, and the air also takes up the liquid fumigant and carries it away from the nozzle so that in the vaporization thereof the cooling effect produced is distributed over a large area. This effectually prevents freezing and obstruction of the needle valve.

In the accompanying drawings constituting a part hereof and in which like reference characters indicate like parts,

Fig. 1 is a front elevational view of my new fumigating apparatus;

Fig. 2 is a side elevational view thereof; and

Fig. 3 is an enlarged, vertical, cross-sectional view along the line III—III of Fig. 2.

The apparatus includes an atomizing chamber or casing 1 of cylindrical form, the end 2 of which carries a nipple 3, having a gate valve 4, adapted to be manipulated by the operating handle 5. A nipple 7 connects the valve 4 with the chamber 6 to be fumigated. The opposite end 8 of chamber 1 is closed by a calibrated plate or dial 9, which is threaded into the same at point 10, and is secured in place by a set screw 11. The pointer 12 is adapted to be operated by knob 13, which is secured to the stem 14 of a needle valve 15, within the chamber 1.

There is further provided a plurality of openings or air ports 16 in such position that in operation air is drawn in through the said ports and over the casing of the valve 15 into chamber 6. To the top 17 of casing 1 is secured a three-way valve 18, adapted to be operated by a handle 19, which is shown in the uppermost position and which is adapted to be placed in positions 20 and 21, as is explained below.

A graduated glass measuring cylinder 22, protected by a metal jacket 23, having an opening therein to allow inspection of the cylinder, is secured in communication with the upper opening of three-way valve 18 by a nut 24. At the upper end of the measuring cylinder 22 is a similar nut 25 which holds a connecting portion 26 for a pipe 27, communicating with the vapor space 28 of a tank 29, adapted to hold the liquid fumigant. A pipe 30 from the side of valve 18 communicates with tank 29 below the liquid level.

The needle valve or automizing device 15 includes a casing, the rear end 31 of which is threaded to receive the stem 14 of the needle valve in threaded adjustable relation. The forward end 32 thereof is tapered, terminating in a small opening or nozzle 33 into which the needle 34, which is secured to stem 14, is adapted to extend. In the upper portion of the casing is a threaded opening 35, in which is secured a tube 36, the upper end 37 of which is expanded and threaded. Said portion extends through an opening 38 in chamber 1 and is secured to the threaded lower end 39 of valve 18, which is welded at point 40 to the chamber 1 in order to maintain the proper relative positions of the parts.

A plate 41 is welded or brazed at 42 to nipple 3 and has an opening 43 in the central portion thereof, cooperating with the tapered end 32 of the needle valve casing. The opening 43 may be adjusted to suit the desired conditions by threading nipple 3 in one or the other direction.

The operation of the device is as follows:

The articles to be fumigated are placed in fumigating chamber 6, and the chamber is evacuated. The handle 19 of three-way valve 18 is placed in the upper position, thereby causing liquid fumigant to flow from tank 29 through pipe 30 and into the measuring cylinder 22 until the proper amount is contained therein, after which the handle 19 is placed in position 20 to cut off a further flow of fumigant. Handle 19 is then moved to position 21, allowing the measured liquid fumigant to flow from measuring cylinder 22, through valve 18, into the casing of needle valve 15. Gate valve 4 is then opened, producing a suction upon the fumigant by reason of the vacuum in chamber 6, causing the fumigant mixed with air, to flow into the said chamber. After the entire dose has been so delivered, valve 4 is closed and handle 19 placed in position 20, when the apparatus is again ready for further operation.

The relative amounts of air and liquid fumigant may be varied either by the adjustment of the opening of the nozzle 33 by means of knob 13, the size of the opening 45 being determined by the movement of point-

ter 12 over the dial 9 or the position of the plate 41 may be adjusted to increase or decrease the amount of air which passes through opening 43.

Although I have described my invention, setting forth a specific embodiment thereof, I am not limited to the details of construction herein set forth. For instance, I may replace the measuring cylinder 22 with a different device for measuring the desired amount of fumigant. Or instead of the vent connection 27 from the top of the measuring cylinder to the fumigant tank 29 I may simply allow the cylinder to vent into the air or to the outside by suitable piping connections. The shape and relative sizes of the various parts may be varied at will without departing from the spirit and scope of my invention.

What I claim is:

1. A fumigating apparatus comprising a measuring cylinder for volatile liquid fumigant carrying some water, a nozzle for receiving the fumigant from the cylinder, a needle valve in the nozzle, a chamber surrounding the nozzle, air ports in the chamber, a fumigating chamber to be evacuated connected with the chamber surrounding the nozzle, whereby when the fumigating chamber is evacuated, an inflow of air is induced through the ports and around the nozzle, and fumigant through the nozzle, the air being sufficient to volatilize the fumigant and prevent freezing of the water carried thereby on the needle valve and in the nozzle due to volatilization.

2. A fumigating apparatus comprising a measuring cylinder for volatile liquid fumigant carrying some water, a nozzle for receiving the fumigant from the cylinder, a needle valve in the nozzle, a chamber surrounding the nozzle, air ports in the chamber, a fumigating chamber to be evacuated connected with the chamber surrounding the nozzle, whereby when the fumigating chamber is evacuated an inflow of air is induced through the ports and around the nozzle, and fumigant through the nozzle, the air being sufficient to volatilize the fumigant and prevent freezing of the water carried thereby on the needle valve and in the nozzle due to volatilization, means for adjusting the relation of the needle valve and nozzle, and means for adjusting the amount of air flowing around the nozzle.

3. A fumigating apparatus comprising a supply tank for volatile liquid fumigant carrying some water, a measuring cylinder connected to said supply tank, a nozzle for receiving the fumigant from the cylinder, a needle valve in the nozzle, a three way valve in the connection between the supply tank and the measuring cylinder and the measuring cylinder and the nozzle, for permitting a flow of liquid fumigant from the

supply tank to the cylinder in one position and from the cylinder to the nozzle in another position, a chamber surrounding the nozzle, air ports in the chamber, a fumigating chamber to be evacuated connected to the chamber surrounding the nozzle, and a valve in said connection.

In testimony whereof, I have hereunto subscribed my name this eighteenth day of

16 September, 1924.

KENNETH A. KILBOURNE.
